CLAIM

The ornamental design for a handset for portable patient infusion system, as shown and described.

DESCRIPTION

FIG. 1 is a front view of a handset for portable patient infusion system showing the new design;

FIG. 2 is a left side view thereof;

FIG. 3 is a right side view thereof;

FIG. 4 is an enlarged top view thereof;

FIG. 5 is an enlarged bottom view thereof;

FIG. 6 is a rear view thereof; and,

FIG. 7 is a front perspective view thereof.

The broken lines in the drawings depict portions of the handset for portable patient infusion system that form no part of the claimed design.
